Primary Examiner — Keith J Wilson(74) *Attorney, Agent, or Firm* — Li & Cai Intellectual Property (USA) Office(57) **CLAIM**

The ornamental design for a repellent sprinkler, as shown and described.

DESCRIPTION

FIG. 1 is a front, right side, top perspective view of a repellent sprinkler showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, left side, bottom perspective view thereof; and,

FIG. 9 is a front, right side, top perspective view of a repellent sprinkler head with a wall mounting hook attached on a right side to replace a ground stake.

The dashed broken lines in the drawing depict portions of the repellent sprinkler that form no part of the claimed design.

The wall mounting hook shown in dashed broken lines in FIG. 9 depict environment that forms no part of the claimed design.
